CLAIM

The ornamental design for a combination pool and sandbox, as shown and described.

DESCRIPTION

FIG. 1 is a top, front, and left side perspective view of a combination pool and sandbox showing our new design;

FIG. 2 is a top plan view thereof, the bottom being plain and unadorned;

FIG. 3 is a front elevational thereof;

FIG. 4 is a right side elevational thereof;

FIG. 5 is a left side elevational thereof; and,

FIG. 6 is a rear elevational thereof.
